[57] CLAIM

The ornamental design for a keyboard central processor control, substantially as shown and described.

DESCRIPTION

FIG. 1 is a front, right side perspective view of a keyboard central processor control showing my new design;

FIG. 2 is a top, front perspective view thereof;
FIG. 3 is a top plan view thereof on a slightly enlarged scale;

FIG. 4 is a front elevational view thereof on a slightly enlarged scale;

FIG. 5 is a rear elevational view thereof.
